UNITED STATES PATENT OFFICE.

HENRY B. STEELE, OF RISING SUN, INDIANA, ASSIGNOR OF ONE-THIRD TO HUGH H. STEELE, OF PARIS, ILLINOIS, AND ONE-THIRD TO WILLIAM C. STEELE, OF RISING SUN, INDIANA.

CARRIAGE-PAINTER'S RACK AND BUGGY-JACK.

1,133,411.

Specification of Letters Patent.

Patented Mar. 30, 1915.

Application filed December 2, 1913. Serial No. 804,328.

To all whom it may concern:

Be it known that I, HENRY B. STEELE, citizen of the United States, residing at Rising Sun, in the county of Ohio and State 5 of Indiana, have invented certain new and useful Improvements in Carriage-Painters' Racks and Buggy-Jacks, of which the following is a specification, reference being had therein to the accompanying drawing.

10 This invention relates to carriage painters' racks and buggy jacks, and has for its object the production of a simple and efficient jack for supporting the frame of a buggy or other vehicle in such a manner as to facilitate the painting or repairing thereof.

Another object of the invention is the production of an efficient means for supporting an object to be painted above the floor in such a manner as to allow access to be 20 had to the under portion thereof, and at the same time support the device in such a manner as to prevent the same from being accidentally thrown into engagement with the floor.

25 With the above and other objects in view this invention consists of certain novel combinations, constructions and arrangements of parts as will be hereinafter fully described and claimed.

30 In the accompanying drawings:—Figure 1 is a perspective view of the rack looking toward the front end thereof. Fig. 2 is a side elevation of the rack showing a buggy or vehicle frame supported thereon. Fig. 3 is a bottom plan view of the rack. Fig. 4 is a perspective view of the rack in a folded or collapsed position. Fig. 5 is an end view of the rack looking at the rear end thereof. Fig. 6 is a transverse section 35

40 through the frame and rollers at the front end of the rack showing the supporting shaft in elevation. Fig. 7 is a vertical section through one of the side arms showing the manner of connecting the same to one 45 of the side bars. Fig. 8 is a detail perspective of one end of the frame showing a locking catch for holding the frame in a set up position when a very light structure is mounted upon the rack. Fig. 9 is a 50 detail perspective of the catch used in connection with the embodiment illustrated in Fig. 8. Fig. 10 is a detail perspective of the lower end of one of the vertically extending links or arms showing the notch

formed therein for receiving the latch illustrated in Figs. 8 and 9. 55

It should be understood that the present invention is especially adapted for use in painting frames, vehicles and the like, and that the device may be readily collapsed 60 when it is so desired for the purpose of conveying the same from place to place, and thereby preventing the rack from taking up unnecessary space.

By referring to the drawings it will be 65 seen that 1 designates the lower frame which comprises a pair of parallel bars, which bars have their respective ends connected by means of the transversely extending rods 2 and 3. The rod 3 constitutes a supporting 70 shaft for the rollers or wheels 4, which wheels are loosely mounted thereon by being journaled upon the reduced portions 5 of the rod 3. A transversely extending stop cleat 6 is carried by the upper face of the 75 side bars of the lower frame 1 and is seated in the notches 7 formed in the upper edge thereof, thereby constituting an efficient means for resisting the longitudinal movement of this stop cleat 6 upon the side bars 80 of the lower frame 1. The ends of the cleat 6 project beyond the side bars of the lower frame 1 as indicated in Fig. 3 so as to constitute stop tongues 8 for receiving the rear 85 pair of vertically extending arms 9. A front pair of vertically extending arms 10 is also mounted upon the side rails of the lower frame 1 and these two pair of arms 9 and 10 support the upper frame 11, which upper frame comprises like the lower frame 1 90 a pair of parallel arms, which arms have their respective ends connected by means of the transversely extending bars 12. A second reinforcing arm 13 is carried near the rear end of the parallel arms constituting 95 the upper frame 11 as is illustrated in Fig. 1. The arms 9 and 10 are pivotally secured to the respective frames 1 and 11 by means of the bolts 14. This structure is also clearly illustrated in Fig. 1. The arms 9 are pivot- 100 ally secured to the lower frame 1 a slight distance beyond the stop tongues 8 so as to cause the arms 9 to be slightly inclined rearwardly in order to allow the arms to engage the stop tongues 8.

The operation of the device is as follows: The entire frame when in a folded or collapsed position such as illus-

trated in Fig. 4 is placed under a carriage frame, which frame is as usual supported upon wheels, and after being placed in such a position the operator will grasp the rear 5 transversely extending rod 12 and lift the upper frame 11 by pulling rearwardly upon the same. The upper frame will then come in contact with the carriage or vehicle frame and by pulling rearwardly upon the upper 10 frame 11 the vehicle frame will be elevated, and after the arms 10 and 11 have passed a point at right angles to the lower frame 1 the arms 9 and 10 will swing upwardly until the arms 9 engage the stop tongues 8 15 which will in this manner efficiently support a carriage frame or other object to be elevated above the floor. The weight of the article will prevent the accidental swinging of the frame 11, relative to the frame 1 or 20 to a collapsed position after once having been set.

I have provided another device comprising an upper and lower frame formed similar to that illustrated in Figs. 1, 2, 3 and 25 4. The rear pair of vertically extending arms 9' are each provided with notch portions 15 formed in the rear edge thereof for the purpose of receiving the pivotally mounted latches 16, which latches are 30 mounted upon the stop ears 8'. These latches 16 may be thrown into engagement with the notches 15, and by being in this position the upper frame 11 can not be swung downwardly upon the lower frame 1 until 35 the latches 16 are removed from engagement with the notches 15. The operator of the device may operate the latches 16 by kicking the same with his foot as it will not be necessary for the operator to release his hold 40 upon the rack and operate the same by hand.

Copies of this patent may be obtained for five cents each, by addressing the "Commissioner of Patents, Washington, D. C."

as these latches 16 are provided with engaging lips 17 projecting from the outer end thereof. It will, therefore, be seen that an efficient means has been produced to prevent the folding of the upper frame 11 down upon 45 the frame 1 without disengaging the latch portions 16; in view of the fact that in order to accomplish this purpose the latches 16 would have to have a vertical movement with the vertically extending arms 9' in order that 50 this swinging movement could take place.

From the foregoing description it will be seen that a very simple and efficient device has been produced for the purpose of supporting a carriage or vehicle frame or other 55 article, and that the rack can be readily folded should it be so desired, and after once having been set will not be likely to collapse.

Having thus described the invention what 60 is claimed as new, is:—

A device of the class described comprising an upper and a lower frame, a transversely extending stop cleat carried by said lower frame, said stop cleat having projecting ends 65 constituting an efficient resisting means, pairs of front and rear vertically extending arms mounted upon said lower frame, said rear vertically extending arms provided with notches and adapted to rest against the 70 projecting ends of said stop cleat, and latches adapted to be thrown into engagement with said notches for preventing the upper frame from being swung downwardly.

In testimony whereof I hereunto affix my 75 signature in presence of two witnesses.

HENRY B. STEELE.
